(57) **CLAIM**

The ornamental design for a set of eye shields, as shown and described.

DESCRIPTION

FIG. 1 is a front, left, top, perspective view of a set of eye shields, shown in an environment, according to our new design;

FIG. 2 is a rear, right, top, perspective view thereof;

FIG. 3 is a front, left, top, perspective view thereof;

FIG. 4 is a rear, right, top, perspective view thereof;

FIG. 5 is a front elevation view thereof;

FIG. 6 is a rear elevation view thereof;

FIG. 7 is a left side view thereof;

FIG. 8 is a right side view thereof;

FIG. 9 is a top plan view thereof; and,

FIG. 10 is a bottom plan view thereof.

In the drawings, the broken lines are for the purpose of illustrating environment only and form no part of the claimed design.

1 Claim, 6 Drawing Sheets
